Fig. 1.

Fig.2.

Fig.3.

Fig.5.

Fig.4.

FIGURE 1 is a perspective view of a casing for storage of an electric toothbrush power unit and brushes therefor embodying our new design, with the casing in opened position;

FIG. 2 is a view similar to that of FIGURE 1, but with the casing closed;

FIG. 3 is a top plan view;

FIG. 4 is a side, elevational view; and

FIG. 5 is a front elevational view.

The side opposite that shown in FIG. 4 is a mirror image thereof.

The dominant features of our design are shown in full lines. The power unit, toothbrush and collapsible tube shown in broken lines are included in FIG. 1 for illustrative purposes only.

We claim:

The ornamental design for a casing for storage of an electric toothbrush power unit and brushes therefor, substantially as shown and described.
